UNITED STATES PATENT OFFICE

2,506,331

BOTTLE CARRIER

William M. Bassichis, Cleveland Heights, Ohio,
assignor to Convenient Carrier Corporation,
Cleveland, Ohio, a corporation of Ohio

Application June 19, 1946, Serial No. 677,869

7 Claims. (Cl. 224—45)

1

This invention relates to bottle carriers of the type formed from fabricated sheet metal.

One of the objects of the invention is to provide a handle for a bottle carrier having laterally disposed arms on the lower ends thereof which constitute separators for the bottles assembled within the carrier.

Another object of the invention is to provide a bottle separator which may be lowered within the carrier to accommodate the ready assembly of the bottles herein and elevated to bottle supporting position upon adjustment of the handle.

Another object of the invention is to provide a bottle carrier which is constructed from a limited number of parts and designed to accommodate the assembly of the structure with a minimum number of connections.

Still further objects of the invention reside in the provision of a bottle carrier which is light in weight, efficient of operation, sturdy of structure and economical of manufacture.

Other objects and advantages more or less ancillary to the foregoing and the manner in which all the various objects are realized will appear in the following description, which, considered in connection with the accompanying drawings, sets forth the preferred embodiment of the invention.

Referring to the drawings:

Fig. 1 is a side elevational view of an improved bottle carrier illustrating the handle and bottle separator in their elevated position;

Fig. 2 is a longitudinal section through the carrier illustrated in Fig. 1 with the handle and bottle separators in their lowered positions;

Fig. 3 is a plan view thereof, a portion of the handle being broken away in the interest of clarity; and

Fig. 4 is a transverse section through the carrier, the section being taken on the plane indicated by the line 4—4 in Fig. 3.

Referring first to Figs. 1 and 3, the bottle carrier comprises a U-shaped cradle 10 formed of a continuous strip of metal of a width slightly greater than the diameter of one of the bottles to be supported thereon. The upper ends of the vertical arms of the cradle 10 are welded or otherwise secured to a band 11 constituting the supports for the sides of the bottles. The band 11 is preferably formed of two U-shaped sections having the free ends 12 thereof bent inwardly and laterally to form a closed guideway for the reception of the vertical arms 13 of the handle or bail 14. The transverse portion of the handle 14 is preferably channeled in order to 55 encompass two

2

increase the rigidity thereof and eliminate the sharp edges on the surface normally grasped when the carrier is in use. The lower free ends of the handle are twisted and bent inwardly to form arms 15 which are disposed as shown in Fig. 3 in the plane of the longitudinal axis of the carrier and parallel to the floor of the base thereof. The ends of the arms are bent around a mandrel to form cylindrical buffers 16 of a diameter which will arrest lateral movement of the bottles disposed in contiguous relation thereto.

When the handle is dropped to its lowered position, the arms 15 will rest upon the base of 15 the frame and thus accommodate the ready entry or removal of the bottles from the carrier. When, however, the loaded carrier is lifted by the handle, the arms 15 and buffers 16 will be elevated into engagement with the side walls of 20 the bottles and thus prevent undue lateral movement thereof.

The top of the handle, when depressed, will lie in a plane below the tops of the crowns of the bottles so that the loaded carriers may be 25 stacked one upon the other.

It will be noted that the framing structure of the improved carrier comprises a single strip of metal that forms the cradle 10, two pieces forming the side and end bands 11 and a single 30 piece that forms the handle and separators. Moreover, that the assembly of the carrier may be effected by merely attaching the side wall strips to the cradle 10; hence, it will be seen that the cost of manufacture of the improved 35 carrier is materially less than other carriers heretofore constructed wherein the separators were made as separate units which were welded or otherwise attached to the frame. It will also be recognized that no sacrifice is suffered in the 40 function of the carrier but on the other hand the improved carrier possesses the added advantages of ready loading, unloading and stability of the load by the improved structure.

Although the foregoing description is necessarily 45 of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

What I claim is:

1. A bottle carrier comprising a rectangular band of sheet metal formed to encompass two

rows of three bottles, a U-shaped band depending therefrom for the support of the bottoms of the bottles, a handle disposed parallel to the major axis of the rectangular band and mounted on the end walls of the U-shaped band for vertical sliding movement relative thereto, bottle separators formed on the lower ends of said handle, and circular buffers on the ends of said separators disposed between the center and end bottles in the two rows thereof.

2. A bottle carrier comprising a rectangular receptacle for the reception of a plurality of bottles arranged in pairs, a supporting handle mounted on the receptacle, arms formed on the lower ends of the handle, and buffers on the ends of said arms engageable with the side walls of the end pairs of bottles in the receptacle.

3. A bottle carrier comprising a cradle of channel section for the support of a plurality of bottles arranged in rows of pairs, side rails mounted on the vertical arms of said cradle, the ends of the side rails being bent inwardly and laterally defining guideways, a handle mounted for vertical sliding movement in said guideways, the free ends of the handle being twisted and constituting bottle separators, and buffers formed in the ends thereof for engagement with the side walls of four contiguous bottles in the carrier.

4. A bottle carrier comprising a rectangular receptacle for two rows of standing bottles, a handle disposed parallel to the rows of bottles and mounted on the ends of the receptacle for vertical sliding movement relative thereto, bottle separators extending from the lower ends of said handle between the rows of bottles, and buffers on said separators adapted to engage the side walls of four adjacent bottles.

5. A bottle carrier comprising a container including a portion adapted to support a plurality of bottles and a portion adapted to encompass the bottles to retain them on the support, a supporting handle for the container mounted thereon for limited vertical sliding movement, and a lateral extension at the lower end of the handle formed

with an enlarged end adapted to engage four bottles immediately adjacent the enlargement for separating the bottles movable with the handle from a position adjacent the supporting means to a position removed from the supporting means.

6. A bottle carrier comprising a container including a portion adapted to support a plurality of bottles and a portion adapted to encompass the bottles to retain them on the support, a supporting handle for the container mounted thereon for limited vertical sliding movement, and means on the handle for separating the bottles movable with the handle from a position adjacent the supporting means to a position removed from the supporting means, the separating means comprising a laterally extending arm terminating in an enlargement adapted to lie between and engage the sides of four adjacent bottles.

7. A bottle carrier comprising a cradle of channel section for the support of a plurality of bottles arranged in rows of pairs, side rails mounted on the vertical arms of said cradle, the ends of the side rails being bent inwardly and laterally defining guideways, a handle mounted for vertical sliding movement in said guideways, the free ends of the handle constituting bottle separators, and buffers formed in the ends thereof for engagement with the side walls of four contiguous bottles in the carrier.

30 WILLIAM M. BASSICHIS.
